UNITED STATES PATENT OFFICE

OSCAR H. FAIRCHILD, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

HYDROCARBON OIL CONVERSION

Continuation of application Serial No. 191,676, filed May 16, 1927. This application filed April 24, 1930. Serial No. 446,915.

This application is a continuation of my former application, Serial No. 191,676, filed May 16, 1927.

The present improvements relate to hydrocarbon oil conversion, and more particularly to the cracking of hydrocarbon oil under heat and superatmospheric pressure to produce desirable yields of commercial products therefrom.

10 In some of the commercial processes for cracking hydrocarbon oils under heat and superatmospheric pressure as practiced today, it is found to be advantageous to permit oil which has been heated to a conversion temperature while passing through a suitable heating coil mounted in a heating zone to be subjected to a soaking or digesting treatment for a sufficient length of time to prolong the period during which the oil is maintained 15 under the conditions of conversion temperature under superatmospheric pressure.

One of the methods proposed for accomplishing this digesting treatment comprises a tubular structure preferably externally unheated but insulated to prevent loss of heat by radiation through which the oil subsequent to attaining the desired temperature is passed. That is to say, the temperature of the oil while passing through what may be 20 termed the soaking instrumentality may be raised slightly, or the temperature may be maintained at or about the temperature to which the oil was subjected while passing through the initial heating coil. In any event, the oil passing through the soaking instrumentality will not be subjected to as drastic a heating as the initial heating coil.

The principal object of the present invention is to prevent the precipitation of undesirable solid or semi-solid particles in the soaking instrumentality and at the same time maintain a desired velocity of the oil passing therethrough by recirculating regulated portions of the oil which has passed through the 25 soaking instrumentality whereby the velocity of said oil is maintained so as to prevent precipitation. As an incidental advantage to the accomplishment of this object, it will be found that the temperature will be more nearly uniform from inlet to outlet of the digest-

ing instrumentality than where no induced circulation takes place.

Another object of the present invention is to permit the use of a relatively larger tube or tubes for the soaking instrumentality relative to the heating coil, which is of advantage due to the increased time at which the oil can be held at a desired reaction temperature. 35

A still further object of the invention is to decrease friction naturally encountered in the passage of oil through the soaking instrumentality. 40

The single figure in the drawing is a diagrammatic elevational view of apparatus equipped to accomplish the objects of the 45 present invention.

Referring more in detail to the drawing, 1 designates a charging stock inlet line in which may be interposed a valve 2 injecting said charging stock into the upper end of a 50 conventional type dephlegmator 3. While descending through the dephlegmator 3, as is well known, the lighter fractions of said charging stock will vaporize under the pressures employed, while the bulk after acting 55 as a cooling medium passes through the reflux leg 4 and into the line 5. This line 5 communicates with return line 6 adapted to inject said charging stock and reflux condensate into the heating coil 7, which may be mounted 60 in a heating zone 8. Means are provided for returning the reflux and charging stock either under an induced pressure by closing valve 9 in by-pass line 10 and opening valves 11 in the line 12, in which is interposed a pump 13. 65 Or, where it is not desired to impose a mechanically applied pressure on the returning oil, the valves 11 may be closed and the valve 75 90 opened. Regulated portions of the returning liquid may be withdrawn through the line 14, controlled by the valve 15. If it is not desired to feed the charging stock directly to the dephlegmator, it may be fed to the charging line 6 through the line 16, controlled by valve 17. Or, the feed may be split, part of 95 the charge going to the dephlegmator and the rest being charged directly to the line 6.

The oil passing through the heating coil 7 which may comprise unvaporized portions 100 of the charging stock and reflux condensate

will be raised to a conversion temperature, for instance, depending on the character of charging stock and types of products desired, which may range from 750° to 875° F., more 5 or less, while a superatmospheric pressure of from three to several hundred pounds, more or less, may be maintained thereon. The heated oil may discharge through transfer line 18, in which may be interposed a valve 19, into a tubular structure 20 mounted in a suitable container 21. This structure may comprise connected lengths of tubing or a single tube or may take the form of a shell, and may, for convenience, be referred to as 10 15 the soaking or digesting instrumentality.

The container 21 may be filled with any suitable form of insulating material, such as insulating powder 22, if desired. It is the purpose of the soaking instrumentality 20 20 to prolong the period of time during which the oil is subjected to reaction temperature. Therefore, it is of importance that the oil be maintained substantially at or above the desired reaction temperature during its passage 25 through the soaking instrumentality 20, that is, substantially at or above the temperature at which it was introduced thereto. Therefore, it is to be noted that the purpose of the insulating material 22 is to prevent 30 excessive loss of heat by radiation. Some means may be employed to maintain the temperature or even for raising the temperature slightly above the temperature at which the oil enters, but in any event said 35 heat is relatively mild, and it is desirable that the element 20 be not subjected to as drastic a heating as the coil 7 was subjected.

The oil after passing through the soaking element 20 discharges into a relatively narrow, vertically disposed combination separator and pump chamber 23 wherein is disposed a recirculating instrumentality 24 which may take the form of a propeller mounted on the shaft 25 and driven by a 40 motor illustrated diagrammatically at 26. It is to be understood, of course, that while I have shown a propeller as an instrumentality for inducing the recirculation that any other mechanical means for accomplishing 45 this purpose can be utilized within the scope of the invention. The instrumentality 24 is so arranged as to operate at variable speeds, the speed of rotation thereof regulates the velocity of the oil being recirculated and consequently regulates the volume or quantity 50 of recirculated oil relative to non-recirculated or fresh incoming oil through line 18.

The proper speed at which to operate the instrumentality 24 can be determined by preliminary runs on a similar charging stock wherein the minimum speed at which it would be practical to operate the instrumentality would be a speed slightly above that at which carbon precipitation might take place. This 55 minimum speed which can be determined by

experimentation is the optimum speed at which it is desired to recirculate. The recirculated oil passes through a circulating line 27 in which is interposed the valve 28, merging with the transfer line 18, as illustrated.

The excess fluid passes through transfer line 29, controlled by valve 29', being introduced into a conventional type reaction drum 30, which reaction drum may be provided with the cleaning manholes 31, and residue draw-offs 32, controlled by valves 33. Separation of vapors from non-vaporous residual products of reaction takes place in the drum 30, which vapors may be withdrawn through the vapor outlet pipe 34, controlled by valve 35, discharging into the lower end of the dephlegmator 3 wherein the vapors are subjected to the usual dephlegmation.

It may be desirable to maintain a low liquid level of non-vaporous residual products of reaction in the drum 30, and for this purpose it may be desirable to subject the residue to a mild agitation so that the body of residue is kept in movement and the solid or semi-solid particles maintained in suspension and prevented from agglomerating and solidifying. To this end, I may provide a suitable stirrer, illustrated diagrammatically at 36.

Vapors remaining uncondensed after passage through the dephlegmator may be withdrawn through the vapor outlet pipe 37 in which may be interposed a valve 38, condensed in condenser coil 39 and collected as liquid distillate in the receiver 40. The latter may be provided with the gas relief line 41, controlled by valve 42, and with the liquid draw-off line 43, controlled by valve 44.

For the purpose of assisting in the dephlegmation of vapors in the dephlegmator 3, regulated portions of the condensed liquid collecting in receiver 40 may be returned through the line 45, controlled by valves 46, under the influence of the pump 47 interposed therein.

The operation of the process and apparatus should be apparent from the foregoing description. The speed at which the instrumentality 24 is operated regulates the proportion of fluid hydrocarbons which are recirculated, while the pump 13 regulates the amount of fresh charging stock being introduced to the heating coil, this pump 13 also controlling the amount of oil and vapors passing from the chamber 23 through the transfer line 29 to the drum 30.

One effective method of heating the soaking element 20 in the event it should be desired to maintain or slightly raise the temperature therein is to subject the element to the action of gases of combustion passing downwardly countercurrent to the upward flow of oil therethrough, thus maintaining more uniform conditions of temperature therein. The

recirculation itself will assist in the maintenance of more uniform temperature conditions on the oil passing through the soaking element 20.

5 It is obvious, of course, that any desirable temperature and pressure conditions may be maintained throughout the system, the most desirable conditions being within the purview of those skilled in this particular art, depending principally upon the character of the charging stock and the types of products desired. It is to be understood, of course, that I do not wish to limit myself in any way to the apparatus shown, as radical changes may 10 be made therein without effecting the scope of the invention.

I claim as my invention:

A hydrocarbon oil cracking process which comprises flowing the oil in an elongated 20 stream of restricted cross-sectional area through a heating zone and heating the same therein to cracking temperature under pressure, thence circulating the thus heated oil, substantially without further application of 25 heat thereto, through a soaking zone in a heat insulated stream of restricted cross-sectional area at a temperature near that at which the heated oil left the heating zone, effecting substantial conversion of the oil during such circulation thereof through the soaking zone, then removing the converted oil from the 30 soaking zone and splitting the same into two sections, injecting one of said sections into the hot oil stream passing from the heating zone to the soaking zone in the direction of flow of the heated oil and under sufficient velocity to substantially prevent carbon precipitation 35 from the oil while circulating through the soaking zone, introducing the other of said sections of converted oil into a separating zone and separating the same therein into vapors and residue, and dephlegmating and condensing the separated vapors.

40 In testimony whereof I affix my signature.
